UNITED STATES PATENT OFFICE.

ROBERT C. SCHOFIELD, OF FREEPORT, ILLINOIS.

ADJUSTABLE TONGUE-HOUND FOR WAGONS.

1,215,416.

Specification of Letters Patent. Patented Feb. 13, 1917.

Application filed November 2, 1916. Serial No. 129,137.

To all whom it may concern:

Be it known that I, ROBERT C. SCHOFIELD, a citizen of the United States, residing at Freeport, in the county of Stephenson, State of Illinois, have invented a new and useful Adjustable Tongue-Hound for Wagons; and I do hereby declare the following to be a full, clear, and exact description of the invention, such as will enable others skilled in the art to which it appertains to make and use the same.

This invention relates to an improved adjustable tongue hound, and an object of the invention is to provide a set of hounds of this kind, which are capable of application or attachment to wagons, in which the front axle hounds are of various widths and inclinations.

A further object of the invention is to provide a device of this kind having improved features of construction.

One of the features of construction is to provide a pair of tongue hounds having pivoted slotted gear plate connections with plates which are secured upon the tongue, whereby the tongue hounds may be adjusted to fit front axle hounds, which vary in width and inclination.

In practical fields, the details of construction may necessitate alterations falling within the scope of what is claimed.

The invention comprises further features and combination of parts, as hereinafter set forth, shown in the drawings, and claimed.

35 In the drawings:—

Figure 1 is plan view of the improved adjustable tongue hound, constructed in accordance with the invention.

Fig. 2 is a sectional view partly in plan of the tongue hounds and the tongue.

Fig. 3 is a sectional view on line 3—3 of Fig. 1.

Fig. 4 is a sectional view on line 4—4 of Fig. 2.

45 Referring more especially to the accompanying drawings, 1 designates a tongue, of any suitable construction, preferably tubular, and 2 and 3 designate plates, which are arranged in pairs. The plates of each pair have arches 4 to receive and engage the tongue at its rear portion, there being bolts 5 and 6 passing through the arches and through the tongue to secure the parts to-

gether. The tongue 1 is provided with a flat portion 7 near the plates 2, on which the doubletree 8 is mounted, so that it will have a bearing surface. A metallic strap 9 is secured at one end by the bolt 5, and its other end by the bolt 10, which passes through the doubletree, and through the tongue 1, and may be provided with a nut, not shown, on its lower end, under the tongue, to hold the doubletree in position. Passing through the end portions of the plates 2 are the bolts 11 and 12, and passing through the end portions of the plates 3, are the bolts 13 and 14, which are secured by the usual nuts 15. The bolts 12 and 14 have integral therewith the pinions 16 and 17. Channel iron tongue hounds 18 are provided, and pivoted on the bolts 19 (which are provided with nuts 20), and in the channel irons, are segment gear plates 21 and 22, which have curved slots 23 and 24, through which the bolts 11 and 13 extend, so as to hold the segment plates 21 and 22 between the end portions of the plates 2 and 3, whereby the teeth of the segment plates will engage the teeth of the pinions 16 and 17. When the tongue hounds 18 are in use, they engage the adjacent faces of the end portions of the usual front axle hounds of the front running gear of a wagon. When the front axle hounds vary in width and inclinations, the various nuts 15 and the nuts 20 are loosened, then the tongue hounds 18 are arranged in position, so that they will accommodate themselves to the disposition of the front axle hounds, by manipulating the segment gear plates 21 and 22 and said pinions, after which the various nuts 15 and 20 and their bolts are tightened again, thereby holding the parts in their adjusted positions, with relation to the front axle hounds.

The invention having been set forth, what is claimed as new and useful, is:—

95

In adjustable tongue hounds for wagons, the combination of a tongue and plates, arranged in pairs, and secured to the rear portion of the tongue, of a pair of hound bars having at their ends adjustably pivoted segment plates provided with adjustable pivotal slot and pin connections between the ends of both pairs of plates of said tongue, said segment plates having gear teeth, pinions mounted between the ends of both pairs of plates of said tongue, to be engaged by the

teeth of the segment plates, and bolts passing through the tongue hounds and the segment plates, and through the ends of the plates of the tongue and through the segment plates and the pinions and provided with nuts for holding the various parts in adjusted positions.

Copies of this patent may be obtained for five cents each, by addressing the "Commissioner of Patents, Washington, D. C."

In testimony whereof I have signed my name to this specification in the presence of two subscribing witnesses.

ROBERT C. SCHOFIELD.
